 tion of Massachusetts

Application August 2, 1939, Serial No. 287,985

10 Claims. (Cl. 51—120)

The invention relates to micro-lapping machines, and more particularly to a micro-lapping machine for surfacing plane surfaces.

One object of the invention is to provide a simple and thoroughly practical micro-lapping machine in which a plane surface of a relatively large work piece may be rapidly surfaced to a plane surface of an extremely high quality. Another object of the invention is to provide a micro-lapping machine in which the work piece is rotated and gyrated in a rotary or irregular path while being lapped or abraded by a plurality of rotary and planetarily moved lapping elements. Another object of the invention is to provide a micro-lapping machine for finishing a plane surface by means of a lapping element which is rotated slowly and oscillated rapidly in a planetary or orbital path.

Another object of the invention is to provide a micro-lapping machine for finishing a relatively large diameter work piece by applying a plurality of slowly rotating, rapidly oscillating lapping elements which are bodily and simultaneously oscillated in arcuate paths relative to the surface of the work piece being finished. A further object of the invention is to provide a micro-lapping machine having a plurality of micro-lapping heads each of which is provided with an independent electrically driven lapping element which is rotated and gyrated in a planetary or orbital path and in which the lapping heads are bodily and simultaneously moved in arcuate paths across the face of the surface being finished. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a right-hand end elevation, having parts broken away and shown in section, to more clearly show the improved micro-lapping machine;

Fig. 2 is a front elevation of the improved machine;

Fig. 3 is a fragmentary diagrammatic view showing the hydraulic piping diagram and the electrical control circuit of the machine;

Fig. 4 is a fragmentary plan view of the ma-

chine, showing the driving mechanism for the micro-lapping heads and wheels;

Fig. 5 is a fragmentary vertical sectional view, on an enlarged scale, of the driving and operating mechanism for one of the lapping heads;

Fig. 6 is a fragmentary cross-sectional view, taken approximately on the line 6—6 of Fig. 5, showing the drive mechanism for producing a slow rotation of the lapping wheel;

Fig. 7 is a fragmentary bottom view, on an enlarged scale, having parts broken away and shown in section, of the reduction gear unit for controlling the simultaneous oscillation of the micro-lapping heads;

Fig. 8 is a cross-sectional view, taken approximately on the line 8—8 of Fig. 7, showing details of construction of the speed reduction unit;

Fig. 9 is a fragmentary sectional view, on an enlarged scale, of the gear mechanism for simultaneously oscillating the micro-lapping heads; and

Fig. 10 is a fragmentary view showing the arrangement of the control lever for actuating the cycle start switch and the stop switch.

The improved micro-lapping machine has been illustrated in the drawings, comprising a base 10 which supports a rotatable work supporting platen 11 together with a plurality of work driving pins or studs 12 (only one of which is shown in the drawings), which engage the apertures in a work piece 13 to be finished. The platen 11 is positively driven by means of an electric motor 14 mounted within the base 10 of the machine. The motor 14 is preferably mounted on a pivotally mounted motor support 15 which is supported on a stud or shaft 16. The motor 14 is provided with a driving pulley 19 which in turn serves to rotate a worm 20. The worm 20 meshes with a worm gear 21 and serves to drive the work supporting platen 11 and revolve and gyrate the work driving pins 12 by means of a mechanism substantially the same as that shown in my prior U. S. Patent No. 1,610,527 dated December 14, 1926. The details of the mechanism for rotating the work supporting platen 11, which in my prior patent is a lapping element, and for rotating and revolving the work driving pins 12, have not been illustrated in the present case, since it is not considered to be a part of the present invention. For details of disclosure not contained herein, reference may be had to my prior patent above referred to.

A micro-lapping head 25 is provided for supporting a lapping wheel 26 so as to present a flat operative end surface to abrade the work piece

13. In the preferred construction, a pair of spaced micro-lapping heads are provided including in addition to the head 25 a micro-lapping head 27 which serves as a support for a micro-lapping wheel 28 which is also arranged to present a flat operative face. The lapping wheels 26 and 28 are spaced from each other and are arranged to engage the work piece 13 to be lapped at diametrically opposite positions.

Each of the lapping wheels 26 and 28 are mounted for both a rotary and a planetary movement so that the abrading or lapping surface is moved in an irregular path as the work piece is rotated and gyrated. Each of the heads 25 and 27 are identical in construction. Consequently only one of the heads has been illustrated in detail. The lapping wheel 28 (Fig. 1) is supported at one end of a rotatable spindle 29 which is journaled in eccentrically mounted bearings 30 within a rotatable sleeve 31. The sleeve 31 is rotatably supported in bearings 32 and 33 within the frame of the head 27. The wheel 26 is similarly mounted at the lower end of a rotatable spindle 35 which is similarly journaled in eccentrically positioned bearings within a rotatable sleeve which is in turn rotatably supported within the frame of the head 25.

Both of the heads are arranged so that the rotatable sleeve may be rotated at a relatively fast speed while the eccentrically mounted lapping wheel spindle contained therein is rotated at a relatively slow speed, so that the individual abrasive grains in the lapping wheels 26 and 28 will be moved in irregular paths while in operative contact with the longitudinally movable rotatable work piece 13 to be finished.

The lapping heads 25 and 27 are preferably arranged so that they may be moved in a substantially vertical direction toward and from the work piece 13. A hollow column 36 is rigidly fixed to the upper surface of the base 10. A vertically movable hollow sleeve 37 is slidably mounted within the column 36 and is arranged to support the lapping heads 25 and 27 adjacent to its upper end. The sleeve 37 supports a bracket 38 which serves as a support not only for the lapping heads 25 and 27 but also supports the driving mechanism therefor.

In the preferred construction, in addition to the rotary and planetary movement of each lapping wheel 26 and 28, it is desirable that the heads 25 and 27 be simultaneously oscillated to impart a third movement to the lapping wheels, thus aiding in producing a highly refined micro-finished surface. The heads 25 and 27 are each provided with rearwardly extending arms 39 and 40 respectively which are pivotally supported on a sleeve 41 (only one of which is shown in detail in Fig. 1). The bushing or sleeve 41 is vertically arranged and is rotatably supported by the bracket 38. The arms 39 and 40 are preferably arranged as bell crank levers having inwardly projecting arms 41 and 42 respectively (Fig. 4). The inner ends of the arms 41 and 42 are each provided with intermeshing gear segments 43 and 44 by means of which the arms 39 and 40 together with the heads 25 and 27, respectively, and the lapping wheels 26 and 28, respectively, may be simultaneously oscillated in opposite directions during the micro-lapping operation to impart a relative oscillating movement of each of the heads during the rotary and planetary movement of the lapping wheels supported thereby.

The frame 38 has a rearwardly extending por-

tion 45 (Fig. 4) which serves as a support for an electric driving motor 46. The motor 46 is provided with a pulley 50 which is preferably a multi-stepped V-type pulley (Fig. 1) which is connected by a V-belt 51 with multi-stepped V-pulleys 52 and 53, respectively. The pulleys 52 and 53 are supported by shafts or spindles 54 and 55, respectively, which are rotatably journaled within the sleeves 41.

10 The spindle or shaft 55 also supports a single V-groove pulley 56 (Fig. 4) which is connected by a V-belt 57 with a single V-groove pulley 58 which is mounted on the upper end of the sleeve 31 to rotate the sleeve and thereby carry the spindle 29 and the lapping wheel 28 supported thereby in a planetary path.

15 Similarly, the spindle or shaft 54 (Fig. 4) is provided with a single V-groove pulley 59 which is connected by means of a V-belt 60 with a single V-groove pulley (not shown) which is mounted on the rotatable sleeve supporting the lapping wheel spindle 35 to rotate the sleeve and thereby move the spindle 35 and the lapping wheel supported thereby in a planetary path. This planetary drive for the head 25 has not been illustrated in detail, since it is identical with that shown in Fig. 1 for the head 27.

20 To facilitate a relatively slow rotary movement of the lapping wheel 28 during its planetary motion, the sleeve 31 is provided with a reduced cylindrical portion 65 which is concentric with the axis of the wheel spindle 29. This portion 65 serves as a support for an anti-friction bearing 66 which in turn supports a rotatable sleeve 67. The sleeve 67 carries a gear 68 which is fixedly mounted thereto and which meshes with a stationary internal ring gear 69 carried by the frame of the head 27. The size of the gear 68 is such that it continuously meshes with the gear 69 during the planetary movement of the spindle 29 as produced by rotation of its supporting sleeve 31. The gear 68 has a smaller number of teeth than the fixed gear 69 so that as the gear 68 revolves within the stationary gear 69, a very slow rotary movement is imparted to the lapping wheel spindle 29 to produce a relatively slow rotary movement of the wheel 28 while it is being moved planetarily at a comparatively rapid rate.

25 30 35 40 45 50 55 60 65 70 The sleeve 67 is slidably keyed to the spindle 29 by means of a key 70 so that the spindle 29 may be moved in a vertical direction to apply the desired pressure to the lapping wheel while in operative engagement with the work piece 13.

55 60 65 70 The upper end of the wheel spindle supports an anti-friction bearing 72 which in turn rotatably supports the casing 73 having a cover plate 74 fixedly mounted thereon. A compression spring 75 is supported at its lower end by means of a stud 76 fixedly mounted on or integrally formed with the cap or cover 74. The upper end of the spring 75 is supported by a reduced cylindrical portion or stud 77 formed at the lower end of a sleeve 78. The sleeve 78 is screw threaded within the upwardly extending housing 79. A nut 80 threaded onto the sleeve 78 serves to lock the sleeve 78 in adjusted position relative to the housing 79, so that after the spring 75 has been tensioned as desired it may be locked in adjusted position.

70 75 It is desirable to provide a suitable mechanism for raising the wheel spindle 29 vertically to compress the spring 75 and withdraw the wheel 28 from operative contact with the work when desired. As illustrated in Fig. 5, a link chain 82

is fastened at its lower end to a stud 16. The upper end of the chain 82 is connected to a pivotally mounted block 83 which is pivotally supported by means of a stud 84. The stud 84 is supported on an upwardly extending boss 85 formed integral with the sleeve 78. The bracket 83 is provided with an actuating handle 86 whereby when moved in a clockwise direction (Fig. 5), the chain 82 may be pulled upwardly in a vertical direction to compress the spring 75 and thereby raise the spindle 29 and the lapping wheel 28 from operative engagement with the work piece.

An identical construction is provided for rotating the wheel spindle 35 and also for raising it in a vertical direction. It is, therefore, deemed unnecessary to duplicate illustration of the constructional details of this head which are clearly shown in Fig. 5.

A driving mechanism is provided for oscillating the gear segments 43 and 44 to produce an oscillatory movement of each of the lapping wheels 26 and 28 at a comparatively low rate of speed during their comparatively rapid planetary and slow rotary movements. A speed reducing unit 90 is driven by means of a multi-stepped V-groove pulley 91 (Fig. 1) mounted on the lower end of the shaft of the motor 49. A V-belt 92 drivingly connects the pulley 91 with a multi-stepped V-groove pulley 93 which is mounted on the lower end of a rotatable driving shaft 94 of the speed reducing unit 90. A driven shaft 95 of the speed reducing unit 90 is provided with a rotatable plate 96 which is provided with a T-slot 97 which serves as an adjustable crank plate. A connecting rod 98 is connected at one end by an adjustably positioned stud which is adjustably supported within the T-slot 97 by means of which the crank motion imparted to the end of the connecting rod 98 may be varied as desired. The forward end of the connecting rod 98 is connected to a stud 100 which is carried by a bracket 101. The bracket 101 is fixedly mounted on the arm 41 (Fig. 9) adjacent to the gear segments 43 and 44. As the rod 98 is moved endwise due to the revolution of the adjustable crankpin 99, an oscillating movement is transmitted through the pin 100, to the bracket 101, to oscillate the arm 41 which in turn oscillates the head 25 and the lapping wheel 26. At the same time, through the intermeshing gear segments 43 and 44, the arm 42 is oscillated which transmits a corresponding oscillatory movement to the micro-lapping head 27 and the lapping wheel 28. By adjusting the crankpin 99 relative to the plate 96, the oscillatory movement of the heads 25 and 27 together with the lapping wheels 26 and 28, respectively, may be varied as desired. It will thus be seen that the heads 25 and 27 together with their respective lapping wheels 26 and 28 are oscillated simultaneously and in opposite directions during the rotary and planetary movement of the lapping wheels 26 and 28.

Any standard speed reduction unit may be employed for reducing the speed of the motor pulley 91 to a suitable speed for oscillating the lapping wheels 26 and 28. As illustrated in the drawings, a speed reducing unit is employed, of the type known as the "Heliocentric," manufactured by Universal Gear Corporation of Indianapolis, Indiana. The driven or input shaft 94 carries a pair of eccentrics 105 and 106. The rotatable output or driven shaft member 95 is fixedly mounted to a rotatable plunger holder

107 which travels within a stationary internal gear or rack member which is preferably divided into two parts, namely the internal annular racks 108 and 109. The plunger holder 107 travels within the stationary racks 108 and 109 at the rate of one rack tooth for each rotation of the input shaft 94. The plunger holder 107 is slotted radially and carries a plurality of reciprocable plungers 110 and 111 which are arranged to work into and out of the teeth of the stationary racks 108 and 109. The racks 108 and 109 are keyed to the casing and have the general appearance of an internal ring gear but with definitely differing tooth shapes, the teeth of the racks 108 and 109 being substantially wedge-shaped. Due to the working contact between the arrow-pointed plungers 110 and 111 and the teeth of the racks 108 and 109, respectively, a combination of sliding and rolling wedge action is obtained, forcing rotation with a minimum friction to the plunger holder 107 and the output or driven shaft 95. The input eccentrics 105 and 106 force plungers out under load. A pair of retracting rings 112 and 113 ride in notches formed within the plungers 110 and 111, respectively, to hold them back on the no-load part of their cycle of operation.

A single eccentric and set of plungers and stationary racks may be employed but for a maximum smoothness of operation and balance of working parts, a universal Heliocentric reducer is employed, having the two eccentrics as illustrated, each of which actuates a set of plungers and in operative engagement with a pair of stationary racks. Each set of plungers is timed directly opposite or 180° apart and has a carrying arc of approximately 120°. The total effect is a balanced distribution of driving power over two-thirds of the complete cycle so that a balanced and uniform slow rotation of the output or driven shaft 95 serves to rotate the eccentric or crankpin 99 to oscillate the heads 25 and 27 simultaneously in opposite directions to cooperate with the combined planetary and rotary movements of the lapping wheels 26 and 28 to produce a micro-finished surface of high quality.

To facilitate removal of finished work pieces and insertion of work pieces to be lapped, a power operated lift is provided whereby the micro-lapping heads 25 and 27 may be simultaneously moved to and from an operating position. In the preferred form a fluid pressure operated mechanism is employed, comprising a cylinder 115 which is fixed relative to the base 10 of the machine. A piston 116 is slidably mounted therein and is connected to one end of a piston rod 117. The upper end of the piston rod 117 is connected to an end cap 118 which is fixedly mounted on the upper end of the sleeve 37. When fluid under pressure is admitted to a cylinder chamber 119 below the piston 116, the piston 116 together with the sleeve 37 is moved vertically to raise the head 38 which in turn raises the micro-lapping heads 25 and 27 and the lapping wheels 26 and 28 respectively to an inoperative position. Similarly, when fluid under pressure is admitted to a cylinder chamber 120 above the piston, a downward movement of the sleeve 37 within the column 36 is obtained, thus moving the lapping heads 25 and 27 to shift the lapping wheels 26 and 28 into operative engagement with the work piece 13.

In order to counterbalance the weight of the head 38 and the parts supported thereon, a counterbalance spring 121 is provided. The spring

121 is a compression spring and surrounds the piston rod 117 and is contained within a central aperture in the vertically movable sleeve 37 and is interposed between a plate 122 at the base of the column 36 and an adjustable thrust collar or nut 123 which is screw threaded into a threaded aperture at the top of the column 37. By adjusting the nut 123 relative to the column 37, the compression of the spring 121 may be adjusted as desired. The compression spring 121 is preferably designed and adjusted so that its compression is sufficient to substantially counterbalance the weight of the head 38 and the mechanism associated therewith and mounted thereon. When the head 38 is moved downwardly under the influence of fluid under pressure, the spring is compressed and serves as a cushion to slightly reduce or cushion the approaching movement of thelapping wheels 26 and 28 as they move into operative contact with the work piece 13.

A fluid pressure system is provided for controlling the admission of fluid under pressure to the cylinder 115. A reservoir 125 is formed as a separate unit at the rear of the base 10 of the machine and is connected to the base by a large tubular member 126 (Fig. 1). Fluid is pumped from the reservoir 125 by a fluid pump 127 which is driven by an electric motor 128. The pump 127 forces fluid under pressure through a pipe 129 to a control valve 130. The control valve 130 is preferably a piston type valve comprising a valve stem 131 having formed integrally therewith valve pistons 132 and 133. In the position of the parts as illustrated in Fig. 3, fluid under pressure passing through the pipe 129 enters a valve chamber located between the valve pistons 132 and 133 and passes outwardly through a pipe 134 into the cylinder chamber 119 to move the piston 116 upwardly which in turn serves to move thelapping heads 25 and 27 to an upward or inoperative position. During this movement, fluid within the cylinder chamber 120 is exhausted through a pipe 135 which passes fluid into an end chamber 136 in the valve 130, from which fluid exhausts through a pipe 137 into the reservoir 125.

When the valve stem 131 is moved toward the left (Fig. 3) into its reverse position, fluid under pressure from the pipe 129 entering the valve chamber between the valve pistons 132 and 133 passes outwardly through the pipe 135 into the cylinder chamber 120 to produce a downward movement of the piston 116 against the compression of the spring 121 to move the head 38, lapping heads 25 and 27, and lapping wheels 26 and 28, respectively, into operativelapping engagement with the work piece 13. During this movement, fluid within the cylinder chamber 119 is exhausted through the pipe 134, into a chamber 138 at the right-hand end of the valve 130 (Fig. 3), and out through a pipe 139 which exhausts into the reservoir 125.

A relief valve 140 is provided in the pipe line 128 whereby excess fluid under pressure within the system may be exhausted through a pipe 141 into the reservoir 125.

To facilitate control of thelapping operation, an electrical control apparatus is provided for controlling not only the rotation and gyration of the work piece 13 but also the rotary, planetary, and oscillatory movement of thelapping wheels 26 and 28, respectively. The valve 130 is preferably electrically actuated by means of a solenoid 142 which is operatively connected to the

left-hand end of the valve stem 131 and a solenoid 143 which is operatively connected to the right-hand end of the valve stem 131.

Electric power is supplied from a suitable source of power, indicated by the power lines 150 (Fig. 3). An electric starter button 151 is provided to start thelapping cycle and a stop button 152 is provided whereby the cycle may be stopped and the laps returned to an inoperative position at any time during the cycle, if desired. The push buttons 151 and 152 are preferably operated by means of a manually operable lever 153 (Figs. 1, 2 and 10) which projects from the front of the machine base 10. The lever 153 is pivotally mounted on a stud 154 which is fixedly mounted within the base 10, and the push buttons 151 and 152 are located within the base 10 of the machine. When the lever 153 is moved in a counterclockwise direction (Fig. 10), the push button switch 151 is closed which serves to energize the solenoid 142 to shift the control valve 130 toward the left (Fig. 3) to cause a downward movement of the piston 116 and thelapping heads 25 and 27 and their respectivelapping wheels 26 and 28, and at the same time to set the time delay relay 155 in motion. The downward movement of the head 38 shifts an adjustable stop or dog 156 (Fig. 3) into engagement with the actuating roller of a normally open limit switch 157 to close the switch 157 which in turn operates through a contact switch 158 to start the motor 14 and thereby rotate and/or gyrate the work piece 13 and at the same time start the motor 49 to rotate, revolve, and oscillate thelapping wheels 26 and 28, respectively, to produce the desired and predetermined micro-finishing operation on the work piece 13. Thelapping operation continues for a predetermined time interval according to the setting of the adjustable electrical time delay relay 155. After a predetermined time interval has elapsed, the time delay relay 155 serves to energize the solenoid 143 to shift the valve 130 toward the right (Fig. 3) to cause the piston 116 to move upwardly to move thelapping heads 25 and 27 together with their respectivelapping wheels 26 and 28 to an inoperative position. During this upward movement of the head 38, the adjustable stop or dog 156 recedes from engagement with the limit switch 157 and the switch 157 opens the circuit to operate the contact with 158 which in turn stops the motors 14 and 49 to stop the movement of the work piece 13 and thelapping wheels 26 and 28 so that the finished work piece may be removed from the machine and a new piece to be lapped inserted instead.

A push button switch 160 is mounted on the front of the machine base to control the starting and stopping of the motor 128 which drives the fluid pump 127.

The operation of this machine will be readily apparent from the foregoing disclosure. A work piece 13 is placed in operating position on the work supporting platen 11, and the push button 160 is then actuated to start the fluid pump motor 128. The control knob 153 is then shifted toward the right (Fig. 2) or in a counterclockwise direction (Fig. 10) to actuate the starter switch 151 which starts the cycle of operation so that the micro-lapping heads 25 and 27 together with their respectivelapping wheels 26 and 28 move toward an operative position in engagement with the work piece 13. Movement of the head 38 toward an operative position closes the limit switch 157 which operates through the

starter switch 158 to start the motors 14 and 49 to start a rotary and/or gyrating movement of the work piece 13 and at the same time to start the rapid planetary, slow rotating, and the simultaneous oscillating movements of the micro-lapping wheels 26 and 28 to micro-lap the surface of the work piece 13 for a predetermined time interval after which the electrical time delay relay 155 shifts the control valve 130 to move the lapping wheels 26 and 28 to an inoperative position and during this movement to stop the motors 14 and 49, respectively. If, during the lapping operation, it is desirable for any reason to stop the cycle, the lever 153 may be moved toward the left (Fig. 2) or in a clockwise direction (Fig. 10) to actuate the emergency stop button 152 which breaks the circuit, thus rendering the time delay relay ineffective to immediately return the wheels 26 and 28 to an inoperative position.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a micro-lapping machine having a base, a rotatable work supporting platen, means to rotate said platen, a movable head, power operated means to cause a relative approaching and receding movement between said head and platen, and a pair of spaced lapping heads pivotally mounted on said vertically movable head each including a rotatable, planetarily movable and oscillatable lapping element which are arranged to engage a work piece on diametrically opposite sides of the platen axis, means to rotate and revolve each of said elements, and means simultaneously to oscillate said lapping heads in arcuate paths during the rotary movement of said lap elements and work platen.

2. A micro-lapping machine having a base, a rotatable work supporting platen, means to rotate said platen, a vertically movable head, means to cause a relative approaching and receding movement between said head and platen, and a pair of spaced lapping heads pivotally mounted on said vertically movable head each including a rotatable, planetarily movable lapping element, a motor on said vertically movable head to rotate and revolve said lapping elements, and an oscillating mechanism driven by said motor simultaneously to oscillate said lapping heads in arcuate paths and in opposite directions during the rotary and planetary movement of said lap elements and work platen.

3. In a micro-lapping machine having a base, a rotatable work supporting platen, means to rotate said platen, a vertically movable head, a power operated mechanism to raise and lower said head, and a pair of spaced lapping heads pivotally mounted on said vertically movable head each including a rotatable planetarily movable lapping element, driving mechanism rapidly to move said element in a planetary path and slowly to rotate said lapping element, and means simultaneously to oscillate said heads in opposite directions.

4. In a micro-lapping machine having a base,

a rotatable work supporting platen, a work rotating and gyrating mechanism associated therewith to give a plurality of positive definite rotary and gyrating movements to a work piece supported on said platen during rotation of the platen, a vertically movable head, a power operated mechanism to raise and lower said head, and a pair of spaced lapping heads pivotally secured on said vertically movable head each including a rotary planetarily movable and oscillatable lapping element, means rapidly to move said lapping elements in a planetary path, means slowly to rotate said lapping elements on each of said heads, and means simultaneously to oscillate said heads in arcuate paths during the rotary and gyrating movements of the work supporting platen.

5. In a micro-lapping machine having a base, a rotatable work supporting platen, a work rotating mechanism associated therewith to impart a rotary motion to a work piece supported on said platen, means including a motor within said base to drive said mechanism, a vertically movable head, means including a piston and cylinder to move said head to cause a relative approaching and receding movement between the vertically movable head and platen, a lapping head pivotally mounted on said vertically movable head including a rotatable planetarily movable and oscillatable lapping element, means including an electric motor on said vertically movable head rapidly to move said lapping element in a planetary path, means slowly to rotate said lapping element, and an oscillating mechanism driven by the motor on said head simultaneously to oscillate said head in an arcuate path during the rotary and planetary movement of said lapping element.

6. In a micro-lapping machine having a base, a rotatable work supporting platen, means to rotate said platen, a vertically movable head on said base, a lapping element pivotally supported on said head, means including a piston and cylinder mechanism to move said head vertically to cause an approaching or receding movement between said head and platen, an electric motor on said head, belt connections between said motor and said lapping element planetarily to move said element at a comparatively fast speed, driving means to rotate said lapping element at a relatively slow speed, a speed reduction unit on said head, driving connections between said motor and speed reduction unit, and means including an adjustable crank mechanism actuated by said speed reduction unit which is arranged to transmit an oscillatory movement in an arcuate path to said lapping element during its rotary and planetary movement.

7. In a micro-lapping machine having a base, a rotatable work supporting platen, a work driving mechanism associated therewith which is arranged to give the work piece a plurality of positive and definite rotating and gyrating movements during each rotation of the work supporting platen, a vertically movable spindle, a hydraulic piston and cylinder to raise and lower said spindle, and a lapping head pivotally mounted on said spindle including an electric motor, a lapping element having a flat operative lapping face, operative connections between said motor and said lapping element rapidly to move said element in a planetary path, driving means slowly to rotate said lapping element, and driving connections between said motor and said lapping element to oscillate said element in an

arcuate path during the rotary and gyrating movements of the work supporting and driving mechanism.

8. In a micro-lapping machine having a base, a rotatable work supporting platen, a work driving mechanism associated therewith which is arranged to give the work piece a plurality of positive and definite rotating and gyrating movements during each rotation of the work supporting platen, a vertically movable spindle, a hydraulic piston and cylinder to raise and lower said spindle, a pair of spaced lapping elements pivotally mounted on said spindle arranged to engage a work piece at diametrically opposite positions, a driving motor on said spindle, driving connections between said motor and each of said lapping elements rapidly to move said elements in a planetary path, driving mechanisms slowly to rotate each of said lapping elements, and driving connections between said motor and lapping elements simultaneously to oscillate said lapping elements in arcuate paths and in opposite directions.

9. In a micro-lapping machine having a base, a rotatable work supporting platen, a work rotating mechanism associated therewith to impart a rotary motion to a work piece supported on said platen, means including an electric motor operatively connected to drive said mechanism, a vertically movable spindle, means including a hydraulic piston and cylinder to raise and lower said spindle, a lapping head on said spindle including an electric motor, a lapping element on said head, driving connections between said motor and said lapping element to rotate and planetarily move said lapping element, a control

valve operatively connected to admit fluid to said spindle cylinder, electrically operated means to shift said valve to initiate a lapping operation, a time delay relay operatively connected to terminate the lapping operation after a predetermined time interval, and means including a switch actuated by the relative approaching movement of said head to start the work drive motor and the lap driving motor as the lapping element approaches the work piece.

10. In a micro-lapping machine having a base, a rotatable work supporting platen, a work rotating mechanism associated therewith to impart a rotary motion to a work piece supported on said platen, means including an electric motor operatively connected to drive said mechanism, a vertically movable spindle, means including a hydraulic piston and cylinder to raise and lower said spindle, a lapping head on said spindle including an electric motor, a lapping element on said head, driving connections between said motor and said lapping element to rotate and planetarily move said lapping element, a control valve operatively connected to admit fluid to said spindle cylinder, electrically operated means to shift said valve to initiate a lapping operation, a time delay relay operatively connected to terminate the lapping operation after a predetermined time interval, means including a normally open limit switch which is held fixed relative to the base, and an adjustable dog on said vertically movable head which is arranged so that the switch is closed during the approaching movement of said head to start the work drive motor and the lap drive motor.
